CLAIM

The ornamental design for a video camera accessory, as shown and described.

DESCRIPTION

FIG. 1 is a rear perspective view of a video camera accessory showing our new design;

FIG. 2 is a front perspective view of thereof;

FIG. 3 is an exploded rear and left side perspective view thereof;

FIG. 4 is an exploded rear and right side perspective view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a left side elevation view thereof; and,

FIG. 10 is a right side elevation view thereof.

The broken lines depict portions of the video camera accessory in which the design is embodied that form no part of the claimed design.
